UNITED STATES PATENT OFFICE.

ALFRED G. F. KUBOWSKI, OF BROOKLYN, NEW YORK, ASSIGNOR TO UNDERWOOD TYPEWRITER COMPANY, OF NEW YORK, N. Y., A CORPORATION OF DELAWARE

TYPEWRITING-MACHINE.

1,395,503.

Specification of Letters Patent.

Patented Nov. 1, 1921.

Application filed April 11, 1919. Serial No. 289,203.

To all whom it may concern:

Be it known that I, ALFRED G. F. KUBOWSKI, a citizen of the United States, formerly a citizen of Germany, residing in Brooklyn borough, in the county of Kings, city and State of New York, have invented certain new and useful Improvements in Typewriting-Machines, of which the following is a specification.

10 This invention relates to typewriting machines, and particularly those of the Underwood type of construction, and one object of the invention is to render the type-bar action less noisy. The type-bars are usually arrested by striking a solid stop or anvil just as the types are about to strike the platen; this stop being placed near the type-bar hubs, and the type-bars springing past the arresting point, so as to deliver the type impression upon the platen. One of the features of the present invention is to provide a yielding stop for the type-bars in place of the rigid stop heretofore employed. This stop, which is in the form of a segment, is 20 provided with a yielding support or cushion. Such cushioning means may consist of a felt strip held in place on the usual type-bar segment casting, on top of which strip is suitably secured a thin piece of spring-steel against which the type-bars strike; or said cushioning means may consist of a hardened and tempered spring inserted into a dovetailed groove in the type-bar segment, said spring having a type-bar contact surface or crown. Still other arrangements of cushioning means may be employed, as for instance a series of looped springs may be interposed between the type-bar segment and a thin piece of spring steel, the latter forming the stop for the type-bars.

25 Other features and advantages will hereinafter appear.

In the accompanying drawings,

Figure 1 is a side elevation of an Underwood typewriting machine, showing my cushioning means applied thereto.

Fig. 2 is an enlarged detail of a section of the type-bar segment, showing the type-bar stop and cushioning means.

30 Fig. 3 is a front view.

Fig. 4 is a diagrammatic view, showing the shape of the spring-steel plate prior to being secured in place on the segment.

Figs. 5, 6 and 7 are detail views.

Fig. 8 is a detail sectional view of a somewhat different form of stop and cushioning means from that shown in Figs. 1 to 7.

Fig. 9 is a front elevation of the form shown in Fig. 8.

Figs. 10 and 11 are details.

Fig. 12 is an enlarged sectional view of still another form of stop and cushioning means.

Fig. 13 is a front elevation of devices shown in Fig. 12.

Figs. 14 and 15 show a different form.

Referring to the drawings, key-levers 1, through means of intermediate levers 2, are adapted to swing type-bars 3 upwardly and rearwardly against the front face of a platen 4 mounted in a carriage 5. The type-bars 3 are pivoted at 6 to type-bar segment casting 7, the line of pivots forming an arc.

In order to arrest the types as they are about to strike the face of the platen, I interpose a stop in the path of movement of a type-bar, so located as to be encountered by a type-bar at about the time the type thereof comes in contact with the platen, and preferably I mount said stop and its cushioning means on the type-bar segment.

In the form of device shown in Figs. 1 to 7, I secure a series of looped springs 8 to the segment by means of screws 9, said springs being arranged in the arc of a circle which is concentric with the line of pivots of the type-bars. On the outside of the looped springs, a stop-plate 10 of spring-steel is mounted, said plate being secured at its ends only, by screws 11, which take into the segment casting, spacing washers 12 being interposed between the ends of the plate 10 and the casting. This plate being of spring-steel and very thin, it will be apparent that if it were applied in a perfectly flat condition and secured only by the end screws 11, it might have a tendency to bulge out at the middle. To avoid this, I give the spring an initial bend inwardly as shown in Fig. 4, so that when the ends are subsequently screwed down, the pressure of the plate on the springs will be substantially uniform throughout its length.

In the form of the device shown in Figs. 8 to 11, inclusive, the type-bar segment casting 7 is milled out at 13 to form a groove, which has its edges undercut or dovetailed, and fitting into this groove is a cushioning spring

- 14 of hardened and tempered steel, having the shape shown in Figs. 10 and 11. The types strike the flat outer surface 14^a, which merges at each edge into the small upper end 5 14^b of an S-shaped side terminating in a large bottom 14^c, which fits into the undercut 13. With this form of spring, no separate securing means is necessary, the tension of the spring itself holding it in position. 10 Furthermore, if it is desirable to present a new striking surface for the type-bars in case of wear, the spring may be moved endwise slightly for this purpose.

Figs. 12 and 13 show a cushioning device 15 comprising a segmental piece of felt 15, secured between a type-bar stop-plate 17 and the type-bar segment 7, being secured thereto by screws 18, the type-bar segment having a groove 16 formed therein for the felt.

- 20 In Figs. 14 and 15, the cushion 15 is placed in a channel plate 19, which is secured to the type-bar segment by screws 18, the latter passing through holes in the plate 17.

In each of the above-described forms, the 25 cushion comprises a metal plate against which the type-bars strike. This plate is located nearer the printing point than the usual Underwood universal bar 20, which lies in the usual opening 21 of the segment 30 7 near the pivot 6, and is adapted to be struck by the heel 22 of any type-bar that approaches the platen.

Variations may be resorted to within the scope of the invention, and portions of the 35 improvements may be used without others.

Having thus described my invention, I claim:

1. In a typewriting machine comprising a platen, type-bars having types thereon and 40 pivots for said type-bars, the combination of a single metallic arresting means effective for all of said type-bars and interposed in their path of movement so as to be encountered thereby at approximately the time 45 the types come in contact with the platen, and a resilient support for said arresting means.

2. In a typewriting machine comprising a platen, a segment, type-bars pivoted on the 50 segment, and a universal bar near the type-pivots, each of said type-bars having type at the end remote from its pivot, the combination of a single metallic arresting means supported on the segment and interposed in 55 the path of swing of said type-bars, and so located as to engage each of said type-bars by a portion thereof between its pivot and type-ends at a time when said type comes in contact with the platen, and a resilient support 60 for the arresting means on the segment between the universal bar and the printing point.

3. In a typewriting machine, the combination with a segment, of a series of type-bars 65 pivoted upon its periphery, a universal bar

near its periphery, an annular metallic stop lying in front of the segment between the universal bar and the printing point, means holding said stop to the segment at its ends, and resilient means for supporting it between its ends, to enable it to arrest the type-bars so that they print by their springing. 70

4. In a typewriting machine, the combination with a series of pivoted type-bars, the line of pivots of said bars forming an arc, 75 of a metallic stop having cushioning means supporting it and common to all of said type-bars and forming an arc concentric with the arc formed by the line of pivots, said stop and cushioning means adapted to 80 be encountered by each type-bar at about the time the type thereof comes in contact with the platen, and a universal bar between the stops and pivots.

5. In a typewriting machine, the combination with a segment, of a series of type-bars pivoted upon its periphery, a universal bar near its periphery, an annular metallic stop lying in front of the segment between the universal bar and the printing point, adapted 90 to arrest the type-bars so that they print by springing, devices holding said stop to the segment at its ends, a series of flat springs having bent-over ends to support said stop, and a device holding each spring 95 upon the segment.

6. In a typewriting machine, the combination with a segment, of a series of type-bars pivoted upon its periphery, a universal bar near its periphery, an annular metallic stop 100 lying in front of the segment between the universal bar and the printing point, adapted to arrest the type-bars so that they print by springing, devices holding said stop to the segment at its ends, a series of flat 105 springs behind the stop, each having two bent-over ends to bear against the stop, and a screw for each spring threaded into the segment and substantially concealed behind the stop. 110

7. In a typewriting machine, the combination with a series of type-bars, of a type-bar segment supporting said type-bars, an annular spring-steel plate secured to said segment and adapted to arrest said bars so 115 that the types print by the springing of the type-bars, and cushioning means interposed between said segment and plate.

8. In a typewriting machine, the combination with a series of type-bars, of a type-bar segment comprising pivots supporting said type-bars, a universal bar adjacent the pivots, an annular spring-steel plate secured to said segment between the universal bar and the printing point to arrest the type-bars, 120 and a series of looped springs interposed between said segment and plate to form cushioning means for said type-bars. 125

9. In a typewriting machine, the combination with a series of type-bars, of a type-bar 130

segment for supporting said type-bars, an annular spring-steel plate secured at its ends only to said segment and adapted to arrest the type-bars so that the types print by the 5 springing of the bars, and cushioning means interposed between said segment and plate, said plate having a slight initial curvature, so that said plate will lie flat upon said cushioning means when secured at its ends.

ALFRED G. F. KUROWSKI.
